UNITED STATES PATENT OFFICE.

MAX J. RITTERRATH, OF LOS ANGELES, CALIFORNIA.

LAMP.

Application filed September 27, 1926. Serial No. 137,901.

This invention relates to lamps, and is especially applicable to lamps of a character using an electric current as the source of illuminating power.

5 The invention is especially valuable when it is desired to employ an electric filament lamp or incandescent bulb as the light source.

One important use of the invention is in outdoor illumination and, more especially, 10 illumination of the character in which a portion of the light rays are projected downwardly, to illuminate the roadway, and another portion of the light rays are projected upwardly, to illuminate the upper portion of 15 the lamp housing.

One of the principal objects of the invention is to illuminate the entire lamp housing.

Another important object is to effect the 20 illumination of the lamp housing without the casting of any shadow within the upper portion thereof.

A further object is to effect the foregoing objects by the use of a simply constructed reflector.

25 A still further object is to effect deflection of the upwardly directed light rays in such a manner as to cause said light rays to traverse the entire zone within the lamp housing above the reflector so as to avoid the casting of a shadow by the reflector on the light-transmitting roof of the lamp housing.

The accompanying drawings illustrate the invention.

Figure 1 is an elevation of a lamp constructed in accordance with the provisions of this invention, the lamp housing being partially broken away to disclose the illuminant and the reflector.

40 Figure 2 is a reduced plan view of the reflector shown in Fig. 1, together with its supporting brackets.

Figure 3 is an enlarged vertical section of the reflector on the line indicated by 3—3, Fig. 2.

45 Figure 4 is an enlarged sectional detail showing a fragment of the reflector and lamp housing, together with one of the brackets for supporting the reflector.

The lamp housing is indicated in general 50 at 5, and may be of any suitable construction. In this instance, it is similar in construction to those at present employed to a large extent in city street illumination, and comprises a metal base 6, a metal top 7, an intermediate metal ring or band 8, metal ribs 9 connecting the base 6 and band 8, and

metal ribs 10 connecting the top 7 and band 8. The housing also comprises light-transmitting panes 11 interposed between the ribs 9, and light transmitting panes 12 interposed between the ribs 10. It will thus be seen that a large part of the upper portion of the housing is light-transmitting, as well as the lower portion.

Supported in any suitable manner within the lower portion of the housing 5 is an illuminant 13. The supporting means for the illuminant are not illustrated, nor is it necessary to describe them in detail herein as the construction of said supporting means is well understood in this art and does not have any bearing upon the invention. In the instance shown in the drawings, the illuminant 13 is a filament or incandescent bulb of a type commonly employed at present, preferably a tungsten gas electric bulb. The illuminant 13 is positioned below the level of the band 8, preferably about two-thirds of the distance from the base 6 to the band 8.

55 Suitably supported at approximately the level of the band 8 is a reflector, which is indicated in general by the character 14, and this reflector is constructed as follows: The reflector has an annular reflecting face 15 which extends horizontally and may be of any desired curvature radially of the reflector. In this particular instance, the curvature of the face 15 is upwardly concave, the curve being flatter near the inner portion of the face than near its outer portion. This face may, however, be a plane face or be of any other suitable curvature, the shape depending somewhat on the height that the lamp is to be placed above the street, and the size of area that it is desired to illuminate by the downwardly directed light rays.

60 The reflecting face 15 is positioned in a relation to the illuminant to reflect a portion of the light radiations downwardly and outwardly through the lower light-transmitting portion of the housing.

65 The reflector is provided with an orifice 16, and this orifice may be located in any suitable part of the reflector. In this particular instance, the orifice 16 is centrally of the reflector and terminates the reflecting face 15 inwardly. Projecting from the marginal wall of the orifice 16 is a reflecting face or faces 17. In this particular instance, the reflecting face 17 is continuous 100 around the orifice 16, but it is to be under-

2
stated that it may be discontinuous, if desired, so as to break up the face 17 into a plurality of faces. The reflecting face 17, in this instance, projects upwardly from the inner margin of the reflecting face 15, and also extends inwardly at an angle. The reflecting face 17 may be of any suitable shape for accomplishing the purpose for which it is intended and, in this instance, is frustroconical.

The size of the orifice 16 and the relation of the orifice and the illuminant and said reflecting face 17 is such that the reflecting face 17 reflects another portion of the light radiations upwardly and outwardly through all of the upper light-transmitting portion of the housing that lies outside of the path of the direct rays projected by the illuminant through the orifice, thus insuring against the reflector casting a shadow upon the upper light-transmitting portion of the housing.

It will be clear from the foregoing that some of the upwardly projected light rays will pass unobstructed through the orifice 16 into that portion of the lamp housing above the reflector, and that other upwardly projected light rays will impinge upon the reflecting face 17 and be diverted so as to traverse an annular zone lying within the housing above the reflecting face 15.

The supporting means for the reflector, in the present instance, comprises a pair of brackets 18. Each bracket is constructed as follows: Each bracket has a U-shaped portion 19 of which the intermediate leg extends for a short distance beneath the reflecting face 15, the end legs of the U-shaped portion passing through holes 20 located in the reflecting face 15 near the periphery thereof. Connecting with the ends of the U-shaped portion 19 are downwardly projecting angular arms 21 which removably engage in a socket or sockets 22 formed in the upper face of an inward projection or projections 23 of the band 8. Thus the reflector is simply suspended so as to avoid the casting of shadows by the suspension means, and so as to facilitate placing of the reflector in the housing and removal of the reflector therefrom.

The invention described above functions as follows: Referring particularly to Fig. 3, it will be seen that a portion *a* of the light radiation is reflected by the reflecting face 15 downwardly, so as to illuminate the lower portion of the lamp housing and the street area adjacent to the lamp. It will also be seen that another portion *b* of the light ra-

diation passes without obstruction upwardly through the orifice 16 into the annular zone above the reflector 15 that would be in shadow if the orifice 16 were not provided in the reflector. Furthermore, it will be seen that another portion *c* of the light radiation is reflected by the reflecting face 17 so as to be diverted almost horizontally into the annular zone lying above the reflecting face 15, and especially into that portion of the zone that would be in shadow if the reflecting face 17 were omitted, even though some of the light radiations are permitted to pass through the orifice 16, as mentioned above. The portions *b*, *c* of the light radiations illuminate that portion of the lamp housing above the band 8, and whatever foliage or other objects may be in the path of the light radiations transmitted by the members 12.

From the foregoing, it will be readily understood that I have succeeded in illuminating the lamp housing to best advantage so as to avoid the casting of shadows upon the light-transmitting members of the housing, and that this result has been secured by a comparatively simple construction. Thus, the reflector may be furnished, if desired, as an inexpensive attachment for lamp housings that are already in service, it merely being necessary to remove the special refractory shades now employed around the illuminant, and to then place the reflector 14 in place in the manner shown in Fig. 1.

I claim:—

A lamp comprising a housing provided with upper and lower light-transmitting portions, an illuminant within the lower portion of the housing, and a reflector in the housing between the illuminant and the upper light-transmitting portion, provided with a horizontally extending reflecting face positioned in relation to the illuminant to reflect a portion of the light radiation downwardly and outwardly through the lower light-transmitting portion, the reflector provided with an orifice and with a reflecting face adjacent to the orifice, the size of the orifice and the relation of the orifice and illuminant and last mentioned reflecting face being such that said last mentioned reflecting face reflects another portion of the light radiations upwardly and outwardly through all of the upper light-transmitting portion that lies outside of the path of the direct rays projected by the illuminant through the orifice.

Signed at Los Angeles, California, this 17 day of Sept. 1926.

MAX J. RITTERATH.
